UNITED STATES PATENT OFFICE.

WILLIAM J. PLEWS, OF CLEVELAND, OHIO, ASSIGNOR, BY DIRECT AND MESNE ASSIGNMENTS, TO PLEWS & HUTCHINSON CORPORATION, OF JERSEY CITY, NEW JERSEY, A CORPORATION OF NEW JERSEY.

METHOD OF MANUFACTURING STORAGE-BATTERY PLATES.

Application filed November 24, 1919. Serial No. 340,386.

The invention relates to manufacture of storage battery plates and it is the primary object of the invention to facilitate the quantity production of said plates. In the present state of the art the plates are formed by first casting the grids or cellular metallic plates, and subsequently filling the cells of the grids with the active material. This filling is usually performed manually and after the grids are filled, they must be dried and subjected to other operations incident to preparing the same for use in the battery. With the present invention the process is simplified and expedited by a series of co-ordinated operations through which the plates are successively cast, filled, dried and delivered. The several steps are so timed that each operation is completed during the continuous advancement of the plate and without interference from either preceding or succeeding plates. The invention therefore comprises; first, the novel process of forming the plates; and second, the apparatus by which this process is carried out.

In the drawings:

Figure 1 is a diagrammatic view illustrating the complete process of forming the plates;

Figure 2 is a side elevation and Figure 3 an end elevation of the apparatus for casting the grids and filling the same with active material;

Figures 4 and 5 are respectively a horizontal section and an end elevation through the drying apparatus.

The usual practice in casting the grids is to form the same in separate molds, the molten metal being fed into the mold cavity through suitable sprues. After the casting, the grid must be trimmed to remove the sprues or gates before it is ready for filling with the active material. With my improvement the grids are die cast and are successively produced from the molten metal by the operation of continuously rotating cooperating dies which deliver the cast plate to the filling apparatus. Thus, as shown in Figure 1, A and A' are cooperating rotary dies. B is a bar or strip of the metal from which the grids are to be cast, which is continuously fed into proximity to said dies, and C and C' are heaters for melting the metal slightly in advance of the rotary dies, so that it may be properly fashioned when

brought into contact therewith. Thus, in operation, the metal is continuously fed to the die casting machine and the molded grids are continuously delivered from the dies, as indicated at D. Before disengaging from the dies the grids are engaged by feed rolls E, which continue to advance the same through the filling device G from which they are delivered to a carrier H for transferring the same to the drying oven I.

More in detail, the die casting apparatus is preferably constructed as shown in Figures 2 and 3, in which J is a suitable frame on which the rotary dies A and A' are mounted. These dies are preferably in the form of hollow cylinders with inlet and outlet passages K and K' passing through the journals thereof and serving for the circulation of a fluid medium that maintains the dies at the proper temperature. The heaters C and C', as shown, are electrical heating units having resistor members C² in which the heat is generated, and downwardly-extending heat conducting members C³ which extend into the V-shaped pocket formed between the rotary dies A and A'. The heat conducted into the pocket is sufficient to melt the metallic bar B as rapidly as the metal is used in forming the grids.

Below the rolls A and A' there is mounted upon the same frame J the feed rolls E, which are arranged in pairs to engage the opposite edge portions of the grid. The rolls E are driven through suitable timed mechanism, such as the gear train M, so as to advance the grids at the same speed that they are delivered from the dies A and A' and the grids so advanced are fed between guides and through the filling device G. The latter is preferably in the form of a heart-shaped chamber into which the active material paste is forced under pressure through the supply conduit N and as fast as the cells of the grid enter the chamber, they will be filled with the paste. There are also preferably provided wipers O which scrape off the surplus paste and smooth the surface thereof, said wipers being yieldably pressed against the opposite sides of the plate by the springs P.

After the plates are delivered from the filling device, they are dropped into a rack in the carrier H, which carrier is preferably advanced by a step-by-step movement so as

to register a new groove in the rack with each plate delivered thereto. This will accumulate a series of plates parallelly arranged, which are advanced towards the 5 drying apparatus I.

In the drying of the plates it is highly important to avoid any treatment which will render the active material dense and impenetrable to the electrolyte. Such a result 10 would follow a quick drying operation in a heated oven, while on the other hand, slow drying would consume so much time that it would be difficult to keep up to the rate of casting and filling. I have avoided both objections by subjecting the moist plates to the action of steam under pressure, preferably super-heated. After a short exposure, 15 the pressure is relieved, whereupon the moisture is eliminated, leaving the material in a porous condition.

The apparatus for effecting the drying is shown in detail in Figures 4 and 5, in which Q is a cylinder mounted on the frame R having the counter-weight S for balancing 20 the same. T is a frame pivoted on the frame R, and U are heads for closing the ends of the cylinder Q, which are secured to screw-threaded rods V engaging correspondingly threaded bearings in the frame T. The arrangement is such that by swinging the frame T into one position, it will clear the heads U from the cylinder and permit of the introduction of the plates to be dried, while the swinging of said frame in the opposite 25 direction will bring the heads into registration with the cylinder, whereupon said heads may be clamped by the screws V. The cylinder Q is preferably provided with a jacket Q' surrounding the same, into which 30 exhaust steam is introduced for maintaining any desired temperature, while within the central chamber of the casing live steam is introduced and at a pressure and humidity such as to produce the desired drying effect. Thus, if the plates are exposed to the 35 steam atmosphere at only a comparatively short interval and then relieved of pressure, the moisture will be dissipated and the material left in a porous condition.

50 What I claim as my invention is:

1. The method of producing storage battery plates, comprising the successive casting and advancement of the grids in continuous series, filling the grids with active material during advancement, subjecting 55 the filled plates immediately and before they have had time to dry to a heated atmosphere under pressure, and subsequently relieving the pressure to effect drying of the active material in a porous condition. 60

2. The method of producing storage battery plates, comprising the successive casting and advancement of the grids in continuous series, passing the advancing grids in contact with means for filling the cells 65 with a plastic active material, introducing the filled plates immediately and without preliminary drying into a closed container, subjecting the plates while in said container to an atmosphere of increased pressure and 70 temperature, and finally relieving the pressure to effect drying while leaving the active material in a porous condition.

3. The method of forming filled grids for storage batteries, comprising a progressive 75 melting and die casting of the metal, the advancement of the cast grids in continuous series, and the immediate subjecting the advancing grids to plastic active material under pressure for filling the cells of the grids. 80

4. The method of producing storage battery plates comprising the die-casting of grids in continuous series, filling said grids successively and immediately after the completion of the die-casting operation, and subjecting the freshly filled grids to a drying 85 operation under super-atmospheric pressure and high temperature immediately after the completion of the filling operation.

5. The method of forming plates for storage batteries comprising progressive casting of separate grids in series, feeding such grids continuously from the casting apparatus to a filling device, applying paste to said grids, and subjecting said pasted grids immediately to a drying operation, whereby completed grids are formed in series continuously. 90 95

In testimony whereof I affix my signature,
WILLIAM J. PLEWS.
